J. Bellochio
By his Attorney
Geo. B. Zeeler

UNITED STATES PATENT OFFICE.

JOHN BELLOCCHIO, OF NEW YORK, N. Y.

EXTENSION TABLE.

Application filed January 4, 1927. Serial No. 158,843.

This invention relates to furniture and has particular reference to extension tables or tables having the adaptability of being made longer or shorter.

5 Among the objects of the invention is to provide a table whose top is divided between its ends, the parts being separable from one another, and having an auxiliary leaf housed normally beneath the top and adapted to rise automatically into the plane of the separated sections of the top when the table is extended.

10

Another object of the invention is to provide means whereby a person at one end of 15 the table may lower the auxiliary leaf so as to permit the separated end parts of the normal top to return to their contracted position while the auxiliary leaf lies beneath.

20 With the foregoing and other objects in view the invention consists in the arrangement and combination of parts hereinafter described and claimed, and while the invention is not restricted to the exact details 25 of construction disclosed or suggested herein, still for the purpose of illustrating a practical embodiment thereof reference is had to the accompanying drawings in which like reference characters designate the same 30 parts in the several views, and in which—

Figure 1 is a side elevation of a table made in accordance with my invention, the table being contracted.

Fig. 2 is a plan view of the same.

35 Fig. 3 is a side elevation of the top portion of the table extended.

Fig. 4 is a vertical sectional detail along the broken line 4—4 of Fig. 2.

40 Fig. 5 is a vertical transverse section on the line 5—5 of Fig. 4.

Fig. 6 is a vertical transverse section on the line 6—6 of Fig. 4.

Fig. 7 is a vertical sectional detail on the line 7—7 of Fig. 3.

45 Referring now more specifically to the drawings, but without intending to be limited to the design of the top or other portions thereof, I show my table as comprising a frame having side bars 10 and end bars 11, said frame being supported by any suitable means as corner legs 12. Additional cross pieces are shown at 13, located substantially mid-way between the end bars 11 and the transverse center line of the table 50 top when closed or the frame as a whole.

55 Extending transversely of the frame along

the transverse center line thereof is an angle member 14 preferably of metal, the ends of which are secured to the inner surfaces of the side bars 10 and from which projects 60 downward a guide member 15 of substantially tubular form.

The normal table top comprises two equal parts 16 forming as shown a substantially square table. The parts are separable from each other along a center line 17. Extending downward from each of the parts 16 are tongues or guides 18, each operating along a slot 19 formed along a side rail 10. By means of these tongues 18 each member 16 65 70 is guided with respect to the frame and is maintained in parallelism with the other portion of the top.

Extending beneath the outer edge of each table top portion 16, the edge that may be 75 defined as the end of the table top, are one or more lugs or blocks 20 seated normally in correspondingly formed notches in the end bar 11 of the frame and extending between said blocks 20 and the adjacent cross bar 13 80 of the frame are contractile springs 22 tending to hold the top portion to which the blocks 20 are attached in nested or closed position as shown in Figs. 1 and 2. The top members 16, however, may be drawn away 85 from each other to the position shown in Fig. 2, against the force of the springs 22.

The auxiliary leaf 23 is normally nested beneath the plane of the table top and is supported in recesses 24 formed in the side 90 rails 10. To effect the prompt rise or lifting of this leaf 23 when the sections 16 are drawn apart, I provide a lever 25 pivoted or hinged at 26 to one of the cross bars 13 and extending thence longitudinally of the table 95 through the lower end of a plunger 27 guided for vertical reciprocations in the guide member 15. The plunger 27 is formed with a hole 28 through which the lever 25 extends, the forward or free end of the lever having a 100 handle 29 which swings beneath the remote end bar 11 of the frame. A contractile spring 30, anchored in the other of the cross bars 13, is engaged with the lever and tends by its contraction to lift the same, the plunger 27, and the leaf 23. The strength of the spring 30 may be sufficient to hold the leaf 23 elevated reliably, but for positive holding of the same I may provide one or more buttons or fastening devices 31 at 105 either end of the leaf 23. As indicated best in Fig. 7, each of these buttons comprises

a face plate 32 fixed to a plunger 33 extending into a socket 34 in the adjacent side rail 10, an expansion spring 35 serving normally by bearing against the head 36 at the inner end of the plunger, to hold the button either in its locking position as shown in full lines in Fig. 7 or in its idle position as shown in dot and dash lines. To the end of the plate 32 is fixed a lug 37 which enters the notch or space 24 after it is drawn outward by the operator from its idle position and swung through 180°. The form of the buttons and especially the blocks 37 insures the reliability of their maintaining themselves in positive locking position and whereby no possibility can they be swung accidentally from holding position.

To contract the table, the operator releases the buttons 31 swinging them out of range of the leaf 23 and then depresses the handle end of the lever 25 against the force of the spring 30 with the result that the auxiliary leaf 23 will be drawn directly downward, being guided in such movement by means of the plunger along the guide 15. The handle end of the lever is then preferably locked by suitable means as, for instance, by a stay 38 fixed to the inner surface of one of the end bars 11, the stay having a notch 39 into which the lever 25 will be received and held. The plunger 27 is fixed rigidly at its upper end in a socket member 40 attached to or let into the lower surface of the leaf 23. The ends of the leaf 23 have secured thereto vertical guide pins 41 slidable in bearings 42 formed in the side rails 10 whereby the leaf 23 will be held reliably from rotation around the vertical center.

40 1 claim:

1. In an extension table, a frame, means to support the frame, a normal table top comprising two parts supported upon the frame and slidable along the same toward and from each other for contraction and extension respectively of the table top, means tending automatically to draw the top

members together, an auxiliary leaf nested normally beneath the top aforesaid and located in notched portions of the frame, a plunger rigidly attached to and extending beneath the auxiliary leaf, a lever pivoted to the frame and having sliding connection with the plunger, the free end of the lever extending forward adjacent to one end of the table, and a spring extending between the frame and the lever tending to lift it and the auxiliary leaf automatically bringing it into the plane of the table top when the top members first mentioned are drawn apart.

2. A device as set forth in claim 1 in which the plunger is guided for vertical reciprocations in a vertical tubular guide fixed to and supported by the frame, said guide having a slot within which the lever operates vertically.

3. In an extension table, the combination of a frame having side bars, a pair of normal top members slidable along the frame toward and from each other, an auxiliary leaf, said side bars being notched to receive and hold the auxiliary leaf in nested position when the table top is contracted, means to automatically elevate the leaf when the table top is extended, and means to positively hold the leaf elevated said last mentioned means being rotatable downward out of operative position when said leaf is not used and consisting of buttons mounted on the side bars of the frame, each button including a casing, a face plate therefor, a plunger, said face plate being rotatably mounted on said plunger, spring means engaging the plunger to hold the face plate against the casing, and a block carried by the end of the plate adapted on rotation of said plate to lie in the recess of the side bar and receive the weight of the leaf thereupon.

In testimony whereof I affix my signature.

JOHN BELLOCCHIO.
